UNITED STATES PATENT OFFICE

148,963

DESIGN FOR A ROAD PAVING MACHINE

Clifford Brooks Stevens, Fox Point, Wis., assignor
to Chain Belt Company, Milwaukee, Wis., a cor-
poration of Wisconsin

Application September 13, 1946, Serial No. 133,282

Term of patent 14 years

(Cl. D14—3)

To all whom it may concern:

Be it known that I, Clifford Brooks Stevens, a citizen of the United States, residing at Fox Point, county of Milwaukee, State of Wisconsin, have invented a new, original, and ornamental Design for Road Paving Machine, of which the following is a specification, reference being had to the accompanying drawings, forming part thereof.

In the said drawings:

Fig. 1 is a perspective view of the paver looking at the discharge end thereof;

Fig. 2 is another perspective view of the paver looking at the discharge end from the side of the machine whence it is controlled; and

Fig. 3 is an end view of the paver with the skip shown in dotted lines in a raised position.

The dominant features of my design reside in the portions shown in full lines.

I claim:

The ornamental design for a road paving machine, substantially as shown and described.

CLIFFORD BROOKS STEVENS.
